CLAIM

I claim the ornamental design for a glove, as shown and described.

DESCRIPTION

FIG. 1 is front elevational view of a glove according to an embodiment of the invention.

FIG. 2 is a left side elevational view of the embodiment of FIG. 1.

FIG. 3 is a right side elevational view of the embodiment of FIG. 1.

FIG. 4 is a sectional view of the embodiment of FIG. 1 along line 4-4, as indicated in FIG. 5.

FIG. 5 is a top plan view of the embodiment of FIG. 1.

FIG. 6 is a bottom plan view of the embodiment of FIG. 1; and,

FIG. 7 is a front elevational view of the embodiment of FIG. 1 in its environment.

The rear elevational view of the embodiment of FIG. 1 is a mirror image of the front elevational view, so the rear elevational view has been omitted.

The stippling and shading lines shown in the drawings represent the approximate three-dimensional contour of the design, and are not intended to indicate surface decoration. The unclaimed environment is represented by thick, evenly spaced, dash-dot-dot-dash lines, and forms no part of the claimed design.
